UNITED STATES PATENT OFFICE.

PHILIP B. CURTIS, OF AMESBURY, MASSACHUSETTS, ASSIGNOR TO HIMSELF
AND ALBERT P. SAWYER, OF SAME PLACE.

IMPROVEMENT IN WHIFFLETREES.

Specification forming part of Letters Patent No. 57,248, dated August 14, 1866.

To all whom it may concern:

Be it known that I, PHILIP B. CURTIS, of Amesbury, in the county of Essex and State of Massachusetts, have made a new and useful invention for attaching a horse to and readily releasing him from a carriage, my said invention being a safety apparatus for preventing injury to a carriage or its inmate or inmates by an unmanageable horse; and I do hereby declare the same to be fully described in the following specification, and represented in the accompanying drawings, of which—

Figure 1 is a top view, and Fig. 2 a front elevation, of a carriage-whiffletree furnished with my invention.

In carrying out my improvement I provide the whiffletree A with two eyes or loops, b b, fastened to it at or near its two extremities. Each eye or loop has a friction-roller, c, arranged in it, the loop and roller being as shown in the above-mentioned Figs. 1 and 2, and also in Fig. 3, which is an end view of them and the whiffletree.

Near the middle of the whiffletree I arrange a strap, d, to be fastened to and to go around the whiffletree, and to extend from its front, with two projections or bolt-holders, e e, provided with holes for reception of a bolt, f, to go vertically through them, such bolt having a spring, s, to keep it in place, and such spring being fastened, at or near one end of it, to the whiffletree, and arranged and formed as represented.

B and C are two leather straps provided at their outer ends with snap-hooks g g, or equivalent devices for connecting the traces of a harness to such straps. These straps are carried through the loops b b, and into the space between the projections e e, and one of such straps is there lapped on the other, and both have the bolt f going down through them.

A rope, h, attached to such bolt, is to lead up to and over the dasher of the carriage, and may be fastened to some convenient part thereof.

The safety-spring s is to keep the bolt in the holders e e under ordinary circumstances; but on pulling on the rope h the spring should recede and allow the bolt to be drawn out of the two straps.

In order to connect the horse to the whiffletree the traces of his harness are to be hitched to the snap-hooks of the straps, the thills being carried through the tugs of the saddle in the ordinary way.

In case the animal should become restive or unruly, so as to endanger the carriage or any occupant thereof, or in case it may be desirable to detach the horse from the carriage while he may be running away with it, a person in the carriage will only have to pull on the rope so as to draw the bolt out of the straps, when they will be set free and be drawn through the loops of the whiffletree by the horse, who will thus become disengaged from the carriage.

I am aware that it is not new to apply to a whiffletree an apparatus or means of discharging or disconnecting the traces therefrom for the purpose of separating a horse from a carriage, and therefore I make no claim to such, my invention being a specific mode or a special safety apparatus, or means of accomplishing such a result.

What I claim is—

1. The arrangement and combination of the trace-attachment straps B C, and the bolt f and its holders e e, with the whiffletree A and its end loops b b, the whole being substantially as specified.

2. The combination of the safety-spring with the whiffletree, the bolt f, its holders, and the attachment-straps B C, applied to such whiffletree, as specified.

PHILIP B. CURTIS.
